UNITED STATES PATENT OFFICE.

FRANK LE COCQ AND IRWIN LE COCQ, OF ABERDEEN, SOUTH DAKOTA.

CYLINDRICAL STRUCTURE AND BLOCKS THEREOF.

Application filed March 20, 1922. Serial No. 545,088.

To all whom it may concern:

Be it known that we, FRANK LE COCQ and IRWIN LE COCQ, citizens of the United States, and residents of Aberdeen, in the county of 5 Brown and State of South Dakota, have invented certain new and useful Improvements in Cylindrical Structures and Blocks Thereof, of which the following is a specification.

10 Our present invention relates generally to cylindrical block structures such as sewers, culverts or conduits and to the blocks thereof, our object being the provision of such a structure formed from blocks as well 15 as the blocks of which it is formed, whereby quick ready formation is brought about and a structure promoted involving a minimum of material, which will be water-tight and capable of resisting internal as well as external pressure.

In the accompanying drawings illustrating our invention,

Figure 1 is a section through a cylindrical structure illustrating the practical application of our invention,

Figure 2 is an end view of the key block, Figure 3 is a top plan view thereof,

Figure 4 is a section therethrough taken on line 4-4 of Figure 3,

30 Figure 5 is an end view of the invert block,

Figure 6 is a bottom plan view thereof,

Figure 7 is a section therethrough on line 7-7 of Figure 5,

35 Figure 8 is an end view of one of the wall blocks,

Figure 9 is a plan view of one of the wall blocks looking at the outer face thereof, and

40 Figure 10 is a section therethrough taken on line 10-10 of Figure 8.

Referring now to these figures, we employ in the formation of a cylindrical structure, such as a sewer, culvert or conduit, a series of wall blocks 10 of similar formation, an invert block 11, which is used at the lowermost point of the structure, and a key block 12 which is used at the uppermost point of the structure, and as will be hereinafter obvious we produce a structure which has in effect an outer shell and an inner lining involving a minimum amount of material in the structure as a whole as well as a minimum amount of labor in its erection, and one which will be water proof and is capable of resisting both internal and external pressures.

Each of the several wall blocks 10, which like the invert block 11 and the key block 12, is generally segmental in form, has outer and inner hollow sections 13 and 14 offset 60 with respect to one another and strengthened by cross ribs 15, both of these sections having along one side edge outstanding ribs 16 and having along the other side edge recesses 17 to receive the ribs 16 of the next 65 adjacent block, it being noted from an inspection of Figure 1 that the several wall blocks 10 are all disposed with their ribs 16 downwardly and their recesses 17 upwardly so that it becomes a simple matter 70 to dispose binding material, that is cement or mortar in the recesses for the seating and securing of the ribs.

In the cylindrical structure, whatever the use to which it is to be put, the wall blocks 75 are successively disposed with their outer sections 13 projecting above their inner sections 14, in series extending upwardly from opposite sides of the invert block 11, the latter of which as shown in Figure 1 and in Figures 5, 6 and 7 has an inner section 18 with side recesses 19 which receive the inner ribs 16 of the lowermost wall blocks 10 upon opposite sides thereof.

The invert block 11 also has an outer section 20 which is hollow and has internal strengthening cross ribs 21 and whose side portions project laterally beyond the sides of its inner section 18 and have side recesses 22 which thus receive the outer ribs 16 of the 90 lowermost wall blocks 10 at opposite sides of the invert block.

The key block 12 shown in Figures 2, 3 and 4 has an outer hollow section 23 provided at its opposite sides with extending ribs 24 95 which may enter the outer recesses 17 of the adjacent side wall blocks upon opposite sides of the key block and also has an inner section 25, also hollow and provided with internal cross ribs 26 as well as with side portions projecting beyond the side portions of the outer section 23 and terminating in ribs 26 which enter the inner recesses 17 of the next adjacent side wall blocks 10 upon opposite sides of the key block.

105 It is thus obvious that the invert block 11 and the key block 12 disposed at diametrically opposite points of the structure serve to finish out and connect the offset overlapping sections of the side wall blocks in such way 110 that by virtue of this connection as well as the structure of the blocks it becomes quite

apparent they are adapted in their connected relation to resist both internal as well as external strains and pressures.

It will also be noted from an inspection of Figures 4, 7 and 10 in particular that the outer walls of the outer sections of each of the segmental blocks is longitudinally offset so that in addition to the circumferential overlapping of the sections of the blocks themselves there is also had in the finished cylindrical structure an overlapping of portions of the blocks in the direction of the axis of the structure and upon its external surface, this structure coating with the circumferential overlapping of the block sections to produce a water proof structure as a whole. In Figure 4 this offset outer wall is indicated at 28, in Figure 7 the offset outer wall appears at 29, and in Figure 10 the offset outer wall is indicated at 30.

We claim:

1. A cylindrical structure of block formation including a series of segmental wall blocks, each having laterally offset inner and outer sections adapting the same to overlapping interlocking connection and provided with ribs and recesses along opposite sides, and diametrically opposed blocks

at opposite sides of which the wall blocks overlap in opposite directions, each of said diametrically opposed blocks having inner and outer sections of different lengths and each having means along the sides of each section to interlockingly engage the side ribs and recesses of the offset sections of adjacent wall blocks upon opposite sides thereof.

2. A cylindrical structure of block formation including a series of segmental wall blocks, each having laterally offset inner and outer sections adapting the same to overlapping interlocking connection, and diametrically opposed blocks at opposite sides of which the wall blocks overlap in opposite directions, each of said diametrically opposed blocks having inner and outer sections of different lengths to interlockingly engage the offset sections of adjacent wall blocks upon opposite sides thereof, said wall blocks and said diametrically opposed locking blocks having relatively engaging ribs and recesses extending along the side edges of the inner and outer sections of each thereof.
